PROCESS AND APPARATUS FOR DISTILLATION OF BITUMINOUS MATERIAL

Filed July 7, 1921

UNITED STATES PATENT OFFICE

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA

PROCESS AND APPARATUS FOR DISTILLATION OF BITUMINOUS MATERIAL

Application filed July 7, 1921, Serial No. 483,053, and in Germany November 6, 1919.

The invention relates to a process and arrangement for the distillation of bituminous material for the purpose of obtaining original tar, i. e., tar that has not as yet been rectified or subjected to distillation, having for its principal objects to avoid overheating of said substances and a secondary decomposition of the oils, and to conserve heat, by avoiding direct firing and by tempering the heating gas by an admixture of air.

In the distillation of bituminous substances for obtaining primary, or original tar, that is tar that has not been subjected to distillation or rectification as yet for the removal of other elements, it is a fundamental prerequisite to avoid overheatings, even of only a local character, and thus secondary decomposition of the resultant oils. In the direct firing of such retorts it is not possible in actual practice to obtain a careful regulation of the heat, especially such regulation as is required for the distilling chambers of fireproof material when they are disposed as is usual. To this must be added that chamotte and similar fireproof stones possess so poor a heat-conductivity coefficient that the efficiency of the distilling device becomes low.

The invention entirely dispenses with the direct firing of the distilling chambers for such distillation and effects such heating by means of a gaseous heat carrier which has been previously charged with the requisite quantity of heat. For that purpose the amount of heat produced by the burning of a gas or some other fuel outside of the distilling device proper and possessed of a high temperature is tempered by the admixture of surplus air, to such an extent that with due consideration of the requisite drop in temperature, the temperature necessary for the heating of the distilling chambers is afforded. As a result of this equalization or tempering purely local overheating can also be avoided, and also the lowering of the temperature renders the use of iron heating jackets for the distilling chambers possible as a general rule. By this means, not only is the efficiency of the heat transmission to the material to be heated increased considerably

but also a better regulation of the heating is at the same time effected.

The quantity of air forming the heat carrier yields its heat surplus over and above the average distilling temperature, to the distilling chambers and leaves the distilling chambers still at a relatively high temperature. The heat losses which would otherwise result are avoided, and the heat surplus rendered serviceable for the process, by conducting the waste heat in each case through a heat recovery plant to impart heat thereto and in which the air required at a later time for the burning and diluting of the healing gases is preheated accordingly. In this manner, there practically results a cycle as regards the heat, during which the heat quantity left after the average distilling temperature has been abstracted, is, as it were, continuously kept in the process and need not be produced anew upon each reversal and only the heat actually consumed in carrying out the distilling process (with some waste as described below) needs to be produced anew.

As the waste heat naturally leaves the heat recovery plant with a certain heat surplus still remaining in it, it might appear advisable to utilize the gases thus remaining from the heat recovery plant over again for dilution; this, however, is not practicable for the following reasons: In the first place, it is always necessary to use fresh air anyway for bringing about the combustion, while, on the other hand, a greater or lesser part of the waste heat would also have to be withdrawn from the process as newly produced surplus. The above mentioned use of the waste heat over again therefore could not be carried out without a loss anyway. On the other hand, the process of working with new air at any time during the different stages of the process, has the advantage that by the use of new air the same initial conditions are always created over again, whereby the desired accuracy in regulating the temperature can be obtained in the most reliable manner.

In order to make the invention clearly understood there is shown in the accompanying drawing means for carrying the same into

practical effect, without limiting the invention to the particular construction which is shown for the purposes of illustration and explanation. In said drawing:—

5 Fig. 1 is an elevation, partly in section, of a distillation plant embodying a form of the physical part of the invention and adapted for carrying out said process.

Fig. 2 is a horizontal section, on a larger 10 scale, of one of the distillation chambers.

Fig. 3 is a fragmentary enlarged view of the top of the left hand retort shown in Fig. 1.

A series of distilling devices *a* are connected by pipe connections *b* and *c* to the conduits *d* and *e* which lead to the regenerators *f* and *g* built after the fashion of the stone blast heaters. Each of the regenerators *f* and *g* are connected with the chimney by connections *r*, *r'* which can be closed to the chimney 15 at *u*, and are connected with the outside air by connections *s*, *s'* which can be closed to the outside air at *t*. The central shafts *h* and *i*, of the respective regenerators *f* and *g*, are connected with the conduits *d* and *e*, respectively, and are provided with means for producing gas flames *k* and *l*, which gas flames burn constantly in the respective shafts *h* and *i*. In one of the operating stages the outside 20 air acting as the gaseous heat-carrier enters through the air pipe *s* and flows through and is preheated by the heat stored up in the fire-proof checker work of the regenerator *f* which has been highly heated by absorption 25 of heat from the waste heat of the preceding operating stage, and in passing through the regenerator *f* the atmospheric air is preheated prior to its passing through the shaft *h* to the gas feed *k*, where a further rise in the 30 temperature of the atmospheric air takes place while a part of the atmospheric air is burnt. At this temperature, which is assumed at about 550° C., the gas enters, 35 through conduit *d* and connection *b*, the heating shaft *m* of the distilling devices or retort 40 structures *a*, which retort structures consist of masonry walls in which a stationary iron cylinder *n* that forms the retort is arranged in spaced relation. Inside of but spaced from the iron cylinder *n* there is provided a slowly 45 rotatable sleeve *o* made after the fashion of the brown coal distilling retorts, which sleeve *o* consists of rings overlapping each other in a Venetian-blind manner. These sleeves *o* 50 are supported for rotation at their upper ends *o'* by a vertical axial drive shaft *o''* which may be driven from below in the usual and well known manner, for instance, as shown in the Norwegian Patent No. 18935. The annular space of shaft *m* between *n* and the 55 masonry wall is divided by a vertically extending partition *p* in shaft *m*, so that the gases entering through *b*, after washing around the jacket, will leave the shaft *m* of the distilling device *a* through the pipe *c*. 60 The fresh material *q* to be distilled is intro- 65

duced into the retorting space within the cylinder *n* at any time at the top into the annular space between *n* and *o* and gradually passes downwardly; in this manner, due to the uniform heating, the primary or original tar is expelled and, by reason of the immediate passage of the gases into the inner space of the member *o*, a subsequent decomposition is also obviated, said gases being led off from the fixed annular gas collector *o''*, into which the central portion of the upper ring of the sleeve *o* telescopes, and passes out of said fixed annular gas collector through conduit *o'''* from which it is conducted for further treatment or use. A hood *o⁴* surmounts the collector *o''* 70 to direct the bituminous material to the space between the sleeve *o* and wall *n*. The gaseous heat-carrier leaving the distilling devices through the connections *c* passes into the conduit *e* to enter the shaft *l* of the heat storer *g*, whose air connection *s'* is closed during such flow of gases, and from the heat storer *g* the gases flow out through the shaft *r'* which is connected with the chimney; in this connection the waste heat gases are highly preheated 75 accordingly by the burner *l* prior to flowing through the checkerbrick in the regenerator chamber *g* to yield sufficiently intense surplus heat to the checkerwork of the regenerator *g* so as to store up sufficiently intense heat in the checkerwork for heating up air upon reversal. From the regenerator *g* the cooled waste gaseous-carrier passes to a chimney through the connection *r'* and enters the chimney relatively cool. This operation can be 80 reversed by proper adjustment of the air and flue valves *t* and *u*, to cause the entrance of air at *s'* and its exit at *r*.

For the feeding of the surplus air at any time, to temper it so as to have the proper temperature after being flame heated, the main prerequisite is that the surplus air is fed to the air current forming the heat-carrier before the heat-carrier reaches the distilling devices. Locating the permanent gas supply in the path of the carrier as described has the advantage that a special reversing of the gas current contrary to the air and chimney connections is rendered entirely superfluous. In this connection the heat of the gas flame burning constantly in the regenerators is first imparted to and transmitted by the waste heat-carrier (air) from the devices *a* to the fire proof checker work in order to be stored therein to be later absorbed by and conducted back into the process by the fresh air at the time of the draft reversal, which draft reversal takes places about every half hour. Aside from the small losses, in this manner of operation, the amount of gas required by continuous burning of the gas flames *k* and *l* will not be more than an amount which would be required and that would correspond to a doubly large gas-supply which would be required were the 100 105 110 115 120 125

burners *k* and *l* used only during the time in which their respective regenerators were serving as an air preheater. It is also easier to regulate the gas supply to the burners *k* and *l* automatically according to the distilling temperature to be attained when they are both used continuously instead of intermittently.

What is claimed is:—

1. Apparatus for low temperature distillation of bituminous material for the production of tar, in combination: two regenerators operable in alternation for preheating air and for storing of heat; a plurality of distilling devices each comprising a fireproof shaft, an iron jacket therein and spaced from said shaft to provide an annular flue space through which a heating medium flows, a vertically extending partition within said annular flue space for controlling the flow of the heating medium therein, a sleeve within said jacket and spaced therefrom to form a retorting space for passage of bituminous material downwardly therethrough, said sleeve having passages for flow of distilled gases or vapor from said retorting space directly to the interior of said sleeve; a conduit leading from and communicably connected with each regenerator; a conduit leading from each of said distilling devices and communicably connecting the conduit from one regenerator with the annular flue space at one side of the partition therein; another conduit leading from each of said distilling devices and communicably connecting the conduit from the other regenerator with the annular flue space at the other side of the partition therein; a shaft communicably connected with each regenerator; a gas burner in each shaft disposed in the path of flow of the heating medium to and from the regenerator; a connection for each of said regenerators and respectively adapted for connecting said regenerators with a draft means, means for controlling the air supply to each of said regenerators; and means for controlling the connections for connecting said regenerators with a draft means; whereby the mere operation of the two last mentioned means effects the simultaneous reversal in flow of the heating medium through the regenerators and all said retorts. 15
2. In the heating of a plurality of low temperature distilling devices with sensible heat of gas burned outside said devices, each having a distilling chamber for distillation of bituminous material and fluing of high heat conductivity arranged for flow of gaseous heating medium into and out of said devices and adapted to maintain material being treated and distilled vapors in said distilling chambers separate from and out of contact with gaseous heating medium in the said fluing of said devices, for the production of tar from bituminous material, the method which consists in: flowing heat-carrier air in a current through a heat recovery plant to preheat the air and then through a gas flame burning outside of said devices, to take up flame heat and radiant heat along with waste gas from gas flame; heating said devices and material being treated therein by passing the preheated and flame heated heat-carrier air and waste gas from the gas flame in a current into and out of said devices by flowing the heat-carrier air current through fluing of high heat conductivity in said devices, which separates the material being treated and distilled vapors from the heat-carrier air current at all times; flowing the waste heat-carrier air in a current from said devices to and through another heat recovery plant to impart excess heat thereto; and subsequently reversing the direction of flow of the heat-carrier air. 70
3. In apparatus for low temperature distillation of bituminous material for production of tar, in combination: a plurality of distilling devices each having flow duct means through which heating medium may flow and having two conduits communicably connected with the flow duct means; two regenerators operable in alternation for preheating air and for storing heat and each having a shaft therein communicably connected with the regenerator chamber; a gas burner in each shaft disposed in the path of flow of air to and from the regenerator chamber; a conduit leading from one of said regenerators and communicably connecting the shaft therein with one of the conduits of each of said distilling devices; a conduit leading from the other of said regenerators and communicably connecting the shaft therein with the other of the conduits of each of said distilling devices; means for controlling the air supply to each of said regenerators; and connection means adapted for communicably connecting each of said regenerators with a draft; substantially as specified. 90
4. A process according to claim 2 characterized by maintaining gas flames continuously in each of the heat recovery plants and also by heating the air current after it has flowed out of said distilling devices but before it flows out into the outflow operating heat recovery plant. 105
5. In low temperature distillation of solid bituminous material for production of tar therefrom, the method which comprises: flowing heat-carrier air in a current through a heat recovery plant to preheat the air and then passing the preheated air through a flame to take up flame heat and radiant heat from the flame; flowing the preheated and flame heated heat-carrier air in heat exchange relation to, but out of contact with, a charge of solid bituminous material; distilling said material by heat imparted thereto from the heat-carrier air while the heat- 120
6. In low temperature distillation of solid bituminous material for production of tar therefrom, the method which comprises: flowing heat-carrier air in a current through a heat recovery plant to preheat the air and then passing the preheated air through a flame to take up flame heat and radiant heat from the flame; flowing the preheated and flame heated heat-carrier air in heat exchange relation to, but out of contact with, a charge of solid bituminous material; distilling said material by heat imparted thereto from the heat-carrier air while the heat- 130

carrier air is in indirect heat exchange relation with said material; flowing the waste heat-carrier air in a current out of heat exchange relation with said charge and through another heat recovery plant to impart excess heat thereto; and subsequently reversing the direction of flow of heat-carrier air.
